UNITED STATES PATENT OFFICE

2,600,594

PLIER-TYPE TOGGLE WRENCH HAVING
THIRD JAW

Stanley L. Williamson, Minneapolis, Minn.

Application October 20, 1950, Serial No. 191,237

14 Claims. (Cl. 81—84)

1

My invention relates generally to improvements in wrenches and more specifically to wrenches of the type which may be utilized as pliers or to hold a desired object in the manner of a vise.

An important object of my invention is the provision of a wrench which will grasp and firmly hold objects of various cross-sectional shapes such as thin flat materials, square or other polygonal pieces, or round or tubular members, with equal facility.

Another object of my invention is the provision of a wrench having a relatively fixed jaw and a plurality of movable jaws cooperating to grasp an article at a plurality of widely spaced points about its periphery.

Another object of my invention is the provision of a wrench having a relatively fixed jaw and a pair of relatively movable jaws in which either of the movable jaws may be utilized to cooperate with said fixed jaw to grasp an article to be held, to the exclusion of the other said movable jaw.

In the use of wrenches, generally, valuable time is often wasted in choosing wrenches to fit particular articles to be held or in adjusting a given wrench to fit an article. A still further object of my invention is, therefore, the provision of a wrench as set forth which may be instantly adjusted to accommodate articles of various sizes and shapes.

A still further object of my invention is the provision of novel means for positively maintaining a wrench of the above type in adjusted set position during grasping movements of the jaws thereof.

Another object of my invention is the provision of a wrench as set forth which is relatively simple and inexpensive to manufacture, which is highly efficient in operation, and which is rugged in construction and durable in use.

Another object of my invention is the provision of a novel method of producing an element with my improved wrench.

The above and still further highly important objects and advantages of my invention will become apparent from the following detailed specification, appended claims, and attached drawings.

Referring to the drawings which illustrate the invention and in which like characters indicate like parts throughout the several views:

Fig. 1 is a view in side elevation of a wrench built in accordance with my invention and shown in a gripping position about an article to be held;

2

Fig. 2 is a view corresponding to Fig. 1 but with some parts being broken away and some parts being shown in section;

Fig. 3 is a view corresponding to Fig. 2 but showing a different position of some of the parts;

Fig. 4 is a view corresponding to Fig. 2 but showing a still different position of some of the parts and the adaptation of my novel wrench to the holding of relatively thin flat material;

Fig. 5 is a fragmentary view partly in side elevation and partly in section, showing the adaptation of my novel wrench to a cross-sectionally hexagonal article;

Fig. 6 is a transverse section taken substantially on the line 6—6 of Fig. 3;

Fig. 7 is a transverse section taken substantially on the line 7—7 of Fig. 3;

Fig. 8 is a view in perspective of a rectangular metallic body from which one of the elements of my invention is produced;

Fig. 9 is a view corresponding to Fig. 8, but showing the body split into two equal parts; and

Fig. 10 is a view in elevation showing the split-apart sections of Fig. 9 secured to each other in back-to-back relationship.

In the preferred embodiment of my invention illustrated, an elongated member 1 is shown as comprising a pair of laterally spaced sections 2 and 3 providing a handle 4 at one end and welded or otherwise rigidly secured at their other ends to a relatively fixed jaw 5 provided with gripping teeth 6 and 7 arranged in angularly disposed planes preferably at approximately sixty circular degrees apart. The handle-forming end portion of the members 2 and 3 are formed to provide longitudinally extending upper and lower pairs of inturned flanges 8 and 9 respectively, for a purpose which will hereinafter become apparent. A second jaw 10 is provided with gripping teeth 11 at one end thereof, and at its other end is journalled on a pivot pin 12 extending transversely between the member sections 2 and 3 and riveted or otherwise rigidly secured thereto in spaced relation to the first jaw 5. The movable second jaw 10 is capable of arcuate movements about the axis of the pivot pin 12 toward and away from the fixed jaw 5, and is urged in a direction away therefrom by a coil tension spring or the like 13, anchored at one end in a notch 14 in the second jaw 10 and at its other end in the elongated section 3, as indicated at 15. A movable third jaw 16 is provided with gripping teeth 17 at one end portion thereof, and at its other end is journalled on a pivot pin 18 which

extends transversely between the elongated mem-

ber sections 2 and 3 intermediate the fixed first jaw 5 and the pivot pin 12, and which is rigidly secured to the sections 2 and 3 in the same manner as the pivot pin 12. By reason of the fact that the pivot pins 12 and 18 are in spaced-apart relationship, the arc of movement of the third jaw 16 toward and away from the first jaw 5 is eccentric to the arc of movement of the second jaw 10. The movable jaw 16 is yieldingly biased in a direction away from the fixed jaw 5 by a coil tension spring 19 anchored at one end in a notch 20 in the jaw 16 and at its other end to the elongated section 3, as indicated at 21.

A handle-forming lever 22 has one end pivotally secured to the movable jaw 10 intermediate its ends by a pivot pin 23 and has pivotally connected to the intermediate portion thereof, as indicated at 24, one end of a toggle link 25. A second handle-forming lever 26 has one end pivotally secured to the movable third jaw 16 by a pivot pin 27, and has pivotally mounted to its intermediate portion, as indicated at 28, one end of a second toggle link 29. As shown, the levers 22 and 26 are disposed, the former above the top side of the handle 4 and the latter below the bottom side thereof, and are movable toward and from said handle and in the plane thereof. A pair of spring elements 30 and 31 are secured to the levers 22 and 26 respectively and are interposed therebetween and their respective toggle links 25 and 29 whereby to bias the levers in directions away from the handle 4 in a manner which will hereinafter become apparent. Preferably and as shown, the handle-forming levers 22 and 26 are cross-sectionally U-shaped for the greater part of their lengths, the former being disposed between the sections 2 and 3 and the latter being disposed outwardly thereof. The levers 22 and 26 are bifurcated in the ends adjacent their respective cooperating jaws 10 and 16, the bifurcation of the lever 26 extending sufficiently to permit reception of the elongated member 1 between the opposite sides thereof.

The handle 4 further includes an intermediate member 32 which is welded or otherwise secured to the handle-forming members 2 and 3 and cooperates therewith to define upper and lower channels 33 and 34 respectively which extend longitudinally of the handle 4, the open sides thereof facing in opposite directions toward their respective levers 22 and 26. The bottoms of the channels 33 and 34 are arcuate in cross-section and are formed by buttress teeth 35 and 36 respectively, the thrust or working faces of which are disposed toward the jaws 5, 10, and 16. In other words, the teeth 35 extend arcuately about a common axis extending longitudinally of the channel 33, and the teeth 36 extend arcuately about a common axis extending longitudinally of the channel 34. Preferably and as shown in Figs. 1 and 7, the elongated sections 2 and 3 are provided with a plurality of spaced apertures 37 wherein the member 32 may be welded or otherwise rigidly secured to the sections 2 and 3.

A preferred method of constructing the member 32 is illustrated in Figs. 8 to 10 inclusive, and is accomplished as follows:

A generally rectangular body A is formed from bar stock and is drilled and tapped longitudinally to provide a central-threaded aperture B, the threads thereof being preferably of the well-known "buttress" type. The body A is then split longitudinally on the axis of the threaded hole B as indicated in Fig. 9. The halves of the body A thus formed are placed in back-to-back rela-

tionship as shown in Fig. 10 and welded or otherwise secured fast together to provide the member 32, after which the member 32 is welded between the elongated handle-forming sections 2 and 3 with the thrust faces of the buttress teeth 35 and 36 formed by the threads of the tapped hole B being disposed toward the jaws of the wrench.

Pivotedly mounted on the free ends of the toggle links 25 and 29 are a pair of elongated locking shoes 38 and 39 respectively, the shoe 38 being contained within the channel 33 and the shoe 39 in the opposite channel 34. Each of said shoes is provided with a bearing boss 40 one end of which is received in a bifurcated end 41 on each of the toggle links 25 and 29 and pivotally mounted therein by means of pivot pins 42. As shown best in Fig. 7, the shoes 38 and 39 have arcuate bottom portions defined by buttress teeth 43 and 44 which are adapted to have meshing engagement with the buttress teeth 35 and 36 respectively of the member 32 whereby to independently and positively lock the shoes 38 and 39 against longitudinal movement in one direction with respect to said member 32. The shoes 38 and 39 are independently movable laterally outwardly from meshing engagement with the member 32 to a limiting extent, said outward movement being limited by engagement of lugs 45 projecting laterally outwardly from the shoes 38 and 39 and engaging the adjacent inturned flanges 8 and 9. It will be noted that the springs 30 and 31 urge their respective shoes 38 and 39 in a direction to cause the teeth thereon to have meshing engagement in their respective channels 33 and 34. With reference to Figs. 1 and 4, it will be seen that the location of either of the shoes 38 and 39 longitudinally with respect to the member 32 determines the distance between the fixed first jaw 5 and the movable jaws 10 and 16 when the wrench is in a closed position. For example, when the shoe 39 is in its position of Fig. 2, the distance between the gripping teeth 17 and the jaw 5 is much greater than is the case when the shoe 39 is in its position of Fig. 4. With this arrangement, adjustment of the movable jaws 10 and 16 to accommodate articles of various sizes and shapes is accomplished with a minimum loss of time and with a minimum of effort involved by merely placing the teeth of the fixed jaw 5 into engagement with the article to be held and manually moving the shoes 38 and 39 in a direction to bring their respective movable jaws 10 and 16 into loose engagement with said article. When this is done, the operator merely moves the handle-forming levers 22 and 26 toward their position of Figs. 2 and 4, the resulting toggle action between said levers and their respective links 25 and 29 causing the article to be gripped with the desired pressure. As shown in Fig. 2, the levers 22 and 26 and their respective toggle links 25 and 29 may be moved beyond dead-center relationship so as to cause the wrench to be self-locked on the article held. The degree of looseness of the initial setting of the movable jaws 10 and 16 with respect to the article to be held determines whether or not the levers 22 and 26 and their cooperating toggle links 25 and 29 will move beyond dead-center relationship when moved to their article-gripping positions. A tubular article is indicated in Figs. 1 to 3 inclusive, and indicated by the letter C. Fig. 4 illustrates the manner in which a hexagon nut or the like D is held by the gripping faces 6 and 7 of the fixed jaw 5 and the gripping faces

14 and 17 of their respective movable jaws 10 and 16.

Although the spring 30 and 31 urge the shoes 38 and 39 into tooth-meshing engagement with the member 32, I have found it advisable to provide means for positively moving the shoes into said meshing engagement and preventing accidental release thereof during the gripping operation. A pair of lugs 46 project laterally outwardly from the opposite sides of the bifurcated end portion of the toggle link 25 in radially spaced relationship to the pivot pin 42. The lugs 46 are positioned to engage the overlying flanges 8 when the lever 22 is moved toward the handle 4 and in a direction to move its cooperating movable jaw 10 toward the fixed jaw 5. As the toggle link 25 swings about the axis of the pin 42, engagement of the pin 46 with the flange 8 moves the shoe 38 toward meshing engagement of the teeth 43 thereon with the teeth 35 on the element 32. A pair of lugs 47 projecting laterally outwardly from the bifurcated end 41 of the toggle link 29 in radially spaced relationship to the axis of the pivot pin 42 are engageable with the overlying inturned flanges 9 and operate in the same manner as the above-mentioned lugs 46 to cause the shoe 39 to be positively moved toward engagement of the teeth 44 thereon with the teeth 36 of the member 32.

With reference to Fig. 4, it will be seen that my novel wrench may, if desired, employ but one of the movable jaws in cooperation with the fixed jaw 5 to grip an article therebetween. As shown, the lever 26 and the handle 4 are used independently of the lever 22 to clamp a relatively thin flat article E between the fixed first jaw 5 and the movable third jaw 16.

My invention has been thoroughly tested and found to be completely satisfactory for the accomplishment of the objectives set forth; and, while I have disclosed a preferred embodiment of my novel wrench and a method, it will be understood that the same is capable of modification and that modification may be made without departure from the spirit and scope of the invention as defined in the claims.

What I claim is:

1. In a tool of the class described, an elongated member providing a handle at one end and a first jaw rigid with its other end, a second jaw, means pivotally mounting said second jaw on said member for arcuate movements toward and away from said first jaw, a lever pivotally connected at one end to said second jaw, a toggle link pivotally connected at one end to the intermediate portion of said lever and at its other end to said handle, a third jaw, means pivotally mounting said third jaw on said member for movements toward and away from said first jaw on an arc eccentric to the arc of movement of said second jaw, a second lever pivotally secured at one end to said third jaw, and a second toggle link pivotally connected at one end to the intermediate portion of said second lever and at its other end to said handle.

2. The structure defined in claim 1 in further combination with yielding means urging said second and third jaws in a direction of swinging movement away from said first jaw.

3. The structure defined in claim 1 in which said second and third jaws are yieldingly urged in a direction of arcuate movement away from said first jaw, and in further combination with yielding means independently urging said toggle

links in one direction of swinging movement with respect to their cooperating levers.

4. In a tool of the class described, an elongated member providing a handle at one end and a first jaw rigid with its other end, a second jaw, means pivotally mounting said second jaw on said member between said first jaw and said handle for arcuate swinging movements toward and away from said first jaw, a lever pivotally secured at one end to said second jaw, a toggle link pivotally connected at one end to the intermediate portion of said lever and at its other end to said handle, a third jaw, means pivotally mounting said third jaw on said member intermediate said first jaw and the axis of pivotal movement of said second jaw for arcuate swinging movements toward and away from said first jaw, the axis of pivotal movement of said third jaw being parallel with that of said second jaw, a second lever pivotally secured at one end to said third jaw, and a second toggle link pivotally connected at one end to the intermediate portion of said second lever and at its opposite end to said handle, said levers being movable in the plane of said handle to impart movement to said second and third jaws toward and away from said first jaw.

5. The structure defined in claim 4 in which said levers are movable toward said handle to a point beyond dead-center relationship of each lever with its cooperating toggle link, whereby said jaws are locked in clamping positions about an article held therebetween.

6. In a tool of the class described, an elongated member providing a handle at one end and a relatively fixed first jaw rigid with its other end, a relatively movable second jaw having gripping teeth at one end portion, means at the opposite end of said second jaw for pivotally mounting the same on said member between said first jaw and said handle for arcuate swinging movements of said second jaw toward and away from said first jaw, a lever pivotally secured at one end to the intermediate portion of said second jaw, a toggle link pivotally connected at one end to the intermediate portion of said lever and at its other end to said handle, a relatively movable third jaw having gripping teeth at one end portion thereof, means at the opposite end of said third jaw for pivotally mounting the same on said member intermediate said first jaw and the pivotal connection of said second jaw, a second lever pivotally secured at one end to said second jaw adjacent the gripping teeth thereof, a second toggle link pivotally connected at one end to the intermediate portion of said second lever and at its other end to said handle, said levers being movable in the plane of said handle to impart movement to said second and third jaws toward and away from said first jaw, and yielding means urging said second and third jaws in a direction away from said first jaw.

7. The structure defined in claim 1 in which the pivotal connections between the toggle links and said handle are adjustably movable longitudinally of said handle.

8. In a tool of the class described, an elongated member providing a handle at one end and a gripping jaw rigid with its other end, a second jaw, means pivotally mounting said second jaw on said member for arcuate swinging movements toward and away from said first jaw, a lever pivotally secured at one end to said second jaw, a toggle link pivotally connected at one end to the intermediate portion of said lever, an elongated shoe having pivotal connection with the other

end of said toggle link, said handle defining a longitudinally extended channel the bottom of which is provided with a longitudinally extended series of abutment-forming teeth extending in arcs about a common axis, said shoe being provided with a longitudinally extended series of abutment-forming teeth engageable with the teeth in said channel, the teeth on said shoe extending in arcs about an axis common to said first-mentioned axis when the teeth on said shoe and said channel are in operative engagement, cooperating means on said shoe and said handle for limiting movement of said shoe away from the teeth in said channel in a direction transversely of said handle, yielding means interposed between said lever and said toggle link and urging said shoe toward engagement of the teeth thereof with the teeth on said handle, and cooperating means on said toggle link and said handle for positively locking said shoe in tooth-engaging position in said channel when said lever is moved toward said handle.

9. In a tool of the class described, an elongated member providing a handle at one end and a relatively fixed first jaw at its other end, relatively movable second and third jaws, means pivotally mounting said movable jaws on said member in spaced relation to each other and to said first jaw for independent arcuate movements toward and away from said first jaw, a pair of levers each having one end pivotally connected to a different one of said movable jaws and extending longitudinally of said handle on opposite sides thereof, said handle defining longitudinally extended channels the open side of each of which faces one of said levers and the bottoms of which are provided with buttress teeth extending in arcs about common axes extending longitudinally of said handle, a pair of toggle links each pivotally connected at one end to the intermediate portion of a different one of said levers, a pair of elongated shoes one each pivotally connected to the opposite end of each of said toggle links and longitudinally slidably one each in each of said channels, said shoes being provided with arcuately extending buttress teeth adapted to mesh with the teeth in their respective channels in a manner to lock said shoes against relative movement in a direction away from said jaws but to permit movement thereof in the opposite direction, and yielding means urging said shoes toward engagement of the teeth thereon with the teeth in said channels, said shoes being independently adjustably movable one with respect to the other thereof.

10. The structure defined in claim 9 in further

combination with cooperating means on said handle and said shoes for positively limiting outward movement of said shoes in a direction transversely of said handle.

5 11. The structure defined in claim 9 in further combination with cooperating means on said handle and said toggle links for positively moving said shoes into locking engagement with the teeth in said channels upon movement of said levers toward said handle.

10 12. The structure defined in claim 9 in which said second and third jaws are independently yieldingly biased in a direction away from said relatively fixed first jaw.

15 13. The structure defined in claim 9 in further combination with means for positively limiting outward movement of said shoes in a direction transversely of said handle, said means comprising opposed longitudinally extending flanges on opposite sides of said handle and overlying said channels, and laterally outwardly projecting lugs on opposite end portions of each of said shoes engageable with said flanges upon laterally outward movements of said shoes with respect to their respective channels.

20 14. The structure defined in claim 9 in further combination with means for positively moving said shoes into locking engagement with the teeth in said channels upon movement of said levers toward said handle, said means comprising laterally inwardly projecting flanges extending longitudinally of said handle member, one each thereof overlying one of said channels, and a laterally outwardly projecting lug on the adjacent portion of each of said toggle links laterally outwardly of the pivotal connection therebetween and its respective shoe, each of said lugs engaging an adjacent one of said flanges upon movement of its cooperating lever toward said handle.
